UNITED STATES PATENT OFFICE.

FELICE MOLINI, OF SAN FRANCISCO, CALIFORNIA.

PEA-SHELLING MACHINE.

SPECIFICATION forming part of Letters Patent No. 302,515, dated July 22, 1884.

Application filed April 12, 1884. (No model.)

To all whom it may concern:

Be it known that I, FELICE MOLINI, residing in the city and county of San Francisco, State of California, have made and invented 5 certain new and useful Improvements in Pea-Shellting Machines; and I do hereby declare that the following is a full, clear, and exact description of the same, reference being had to the accompanying drawings.

10 My invention relates to machines for shell-
ing peas; and it consists in the novel construc-
tion, combination, and arrangement of parts
and devices hereinafter described and claimed.

In the drawings referred to, Figure 1 is a
15 side elevation of the machine as affixed to the
table or bench in position for use. Fig. 2 is a
plan or top view of the inclined front of the
machine; Fig. 3, a front view; and Fig. 4, a
20 detail view illustrating the position and op-
eration of the two sets of rollers that seize, ad-
vance, and open the shell and press out the
peas.

A A are the two sides of the frame. B is a
25 slanting feed board or table, upon which the
pods are spread preparatory to being distrib-
uted into the inclined guide-troughs C. This
board B and its inclined continuation C is
30 grooved, so that a number of parallel gutters
or channels are provided, into which the pods
are distributed by the operator, and thus sep-
arated into separate streams or lines. Across
35 the point where these channels turn downward
is a fixed bridge, D, with an apron or strip,
d, along the front, the office of which is to de-
flect the pods as they are pushed forward from
40 the channels b b, and cause them to turn into
the inclined guide-channels c c. At the bot-
tom of this inclined surface are fixed two sets
of rollers, E E' F F', one set slightly in ad-
45 vance of the other, and both sets at an angle
across the front, so that an inclined trough, G,
may be fixed beneath them to catch and con-
duct the shelled peas to one point of discharge.
At the lowest point of the trough G is a hop-
50 per or spout to divide the shelled peas into a
suitable receptacle. The first set of rollers are
set wide apart, and perform the work of split-
ting and pressing forward the pods into the
second set of rollers, that are set sufficiently
55 close together to prevent the passage of the
peas between them while they grasp and draw

in the pods. The peas are discharged into the
trough G from between the two sets of rollers,
while the pods are thrown out at the front of
the outer rollers. One of the feed-rollers, and 55
preferably the upper or driving one, is corrugated;
but the others are smooth face. The
two sets are geared together to obtain regular
motion and in the required direction. A
scraping-edge, H, is mounted in swinging bear- 60
ings h h over the outer rollers to bear against
the face of the top one. A similar strip, I, but
permanently attached, performs the double
service of cleaning the face of the lower roller
and of supporting the outer edge of the in- 65
clined trough G.

The operation of the machine is as follows:
The pods to be opened are spread out by hand
over the feed-board, so that they lie in single
order—one behind the other—in all the chan-
nels, and these rows are then moved forward
20 by the fingers of the operator with a rapid mo-
tion to push them down into the slanting
channels leading to the inclined rollers. At
the bottom of these guides they are caught by
75 the first rollers and drawn in between them.
The second rollers then seize the ends of the
pods, and by compression operate to press out
the peas and draw the pods through to the
front. The peas are gathered at the lower end 80
of the trough, where a drawer or permanent
receptacle as a part of the machine may be pro-
vided.

This machine is adapted to be run by any
suitable power—such as steam, horse, &c.—and 85
to operate upon a large quantity of material,
as the feeding or supplying of the peas is
effected in a rapid manner through the agency
of the corrugated or channeled surfaces.

Having thus fully described my invention, 90
what I claim, and desire to secure by Letters
Patent, is—

1. A machine for shelling peas, comprising
a feed-board or surface with parallel channels
b b, an acutely-inclined continuation of said
channeled surface C, a series of feeding and
pressing rollers, E E' F F', a gathering-trough, 95
G, with a spout, g, and mechanism for driv-
ing said rollers, substantially as hereinbefore
described.

2. The combination, with the inclined sur-
face having parallel channels, of the two sets

of rollers E E' F F', set at an angle across the front thereof, and the trough G below the space provided between the two sets of rollers, substantially as hereinbefore described.

5 3. The combination of the surface formed with parallel channels, as described, the rollers E E', one corrugated and the other smooth, the compression-rollers F F', the scrapers H I,

and a collecting-trough, G, substantially as hereinbefore described.

FELICE MOLINI. [L. S.]
